Patented Dec. 5, 1922.

1,438,118

UNITED STATES PATENT OFFICE.

RICHARD A. KLOHN, OF ST. PAUL, MINNESOTA.

FURNITURE POLISH.

No Drawing.

Application filed May 10, 1922. Serial No. 559,890.

To all whom it may concern:

Be it known that I, RICHARD A. KLOHN, a subject of the King of Great Britain, residing at St. Paul, in the county of Ramsey 5 and State of Minnesota, have invented certain new and useful Improvements in Furniture Polish, of which the following is a specification.

My invention relates to compositions used 10 for polishing furniture and similar articles, and the object is to produce an easily applied furniture polish of high grade at comparatively low cost from the ingredients hereinafter named.

15 In preparing my composition I prefer to use the following ingredients in about the following proportions—viz, in each gallon of the polish I use:

One-half gallon of paraffine oil, thirty- 20 six ounces of alcohol, one ounce of gum mastic, dissolved in the alcohol, fourteen ounces of water, four ounces of vinegar, four ounces of turpentine, three ounces of butter

of antimony, two ounces of oil of citronella.

The mixture should be shaken well until 25 uniform, and then applied with a soft cloth, and wiping off with a dry cloth.

When thus prepared and applied my polish is a fine and durable finish.

I claim:

1. A furniture polish comprising paraffine oil, alcohol, gum mastic dissolved in the alcohol, water, vinegar, turpentine, butter of antimony and oil of citronella.

2. A furniture polish comprising the ingredients mentioned in claim 1 in about the following proportions per gallon of the polish; one-half gallon paraffine oil, thirty-six ounces of alcohol, one ounce of gum mastic, fourteen ounces of water, four ounces of 35 vinegar, four ounces of turpentine, three ounces of butter of antimony and two ounces of oil of citronella.

40 In testimony whereof I affix my signature.

RICHARD A. KLOHN.
